UNITED STATES PATENT OFFICE.

WILLIAM A. BERNARD, OF NEW HAVEN, CONNECTICUT, ASSIGNOR TO THE WILLIAM SCHOLLHORN COMPANY, OF NEW HAVEN, CONNECTICUT, A CORPORATION OF CONNECTICUT.

PAPER-FASTENING TOOL.

1,229,213.

Specification of Letters Patent. Patented June 12, 1917.

Application filed April 9, 1913. Serial No. 760,010.

To all whom it may concern:

Be it known that I, WILLIAM A. BERNARD, a citizen of the United States, residing in New Haven, county of New Haven, and

5 State of Connecticut, have invented certain new and useful Improvements in Paper-Fastening Tools, of which the following is a full, clear, and exact description.

This invention relates to paper fastening 10 tools and more particularly to tools of the plier or lever handle type, which unite sheets of paper or like material by punching up tongues from the respective sheets and threading such tongues through registering 15 slits cut in the sheets by the tool at points adjacent the tongues. Implements of this type generally comprise parallel jaws movable toward and away from each other by pivoted handles, one of such jaws carrying 20 a punch or tongue cutter, a slit cutter, and means for inserting the tongue in an opening or eye of the slit cutter, while the other jaw carries a die plate and a stripper plate. Heretofore, implements of this type have 25 been of quite complicated construction, involving the employment of a large number of parts. As a result, such devices have generally been of a size and weight altogether out of proportion to the light work 30 35 which they perform, and their cost has been considerable, owing to the difficulty and expense entailed in manufacture.

My invention has as its general object the 40 production of a paper fastening tool in which the above mentioned defects are avoided. By my improvements, the tool may be very much more simple, more handy and compact, and considerably smaller and lighter than the prior tools of this type with 45 which I am familiar, and the cost of manufacture may be considerably reduced. These results are obtained, moreover, without sacrificing to any extent the efficiency and durability of the tool; in fact my improvements provide for an especially positive, efficient 50 and reliable operation of the working parts.

More particularly, the invention aims to 55 provide an improved arrangement of the tongue cutting punch with reference to its carrying jaw, whereby considerable superfluous weight is eliminated; to furnish simple, positively operated means for inserting the tongues in the eye of the slit cutter, which means will operate indefinitely under ordinary conditions without getting out of order; to provide improved means for mount-

ing the die plate and stripper plate and for adjusting the stripper plate lengthwise; and to improve various minor features and details of the construction as a whole.

To these and other ends, the invention consists in the novel features and combinations of parts to be hereinafter described and claimed.

In the accompanying drawings,

Figure 1 is a side elevation of a tool embodying my invention, showing the same in its normal open position,

Fig. 2 is a similar view showing the jaws closed,

Fig. 3 is a front end view of Fig. 1,

Fig. 4 is a section on line 4-4 of Fig. 1,

Fig. 5 is a section on line 5-5 of Fig. 1,

Fig. 6 is a section on line 6-6 of Fig. 3,

Figs. 7 and 8 are detail perspective views 75 of the stripper plate and die plate respectively, and

Figs. 9 to 13 inclusive, show diagrammatically several stages in the operation of the tool.

Referring generally to the main parts of the tool, 20 and 21 are jaws of the so-called parallel type adapted to be moved toward and away from each other by means of lever handles 22 and 23, all of which parts are 85 preferably constructed of light sheet metal of channeled cross-section. The jaw 21, which may be termed the lower jaw, is equipped with a die plate 24 and a stripper plate 25. The upper jaw 20 is provided 90 with a tongue cutter or punch 26 and a slit cutter or needle 27, adapted to pass through openings in the stripper plate 25 and die plate 24. The jaw 20 also carries within the punch or tongue cutter 26 a pivoted member 95 28 adapted to insert the tongues cut from the sheets, into the eye of the slit cutter or needle 27; and this tongue inserter 28 is operated by a coöperating projection 29 extending upward from the stripper plate. The stripper plate and die plate are both 100 mounted on the jaw 21 by means of a single screw 30.

Turning now to the detailed construction of the parts above enumerated, it will be 105 noted that the handles 22 and 23 are provided at their forward ends with the usual forked portions 22^a and 23^a respectively. The forked portion 22^a straddles the portion 23^a and said portions are pivoted together 110 by means of a main pivot pin 31. The forward extremity of the forked portion 22^a

of the handle 22 is fixedly pivoted to the jaw 21 by a pin 32, and the portion 23^a of the handle 23 is similarly pivoted to the jaw 20 by means of a pin 33. The parallel motion of the jaws is maintained by means of guide pins 34 and 35 carried by the handles 22 and 23 respectively, at the rear of the main pivot, which guide pins operate in cutaway portions or notches 20^a, 21^a at the rear ends of the respective jaws, and are adapted to coöperate with stop shoulders 20^b and 21^b respectively. A coil spring 36 connecting the rear extremity of the jaw 20 with a pin 37 or the like within the handle 22 normally holds the jaws in their open position, as shown in Figs. 1 and 6. However, the particular means for mounting the jaws in parallel fashion and the particular means for normally holding them open, form no part of the present invention.

The jaw 21 is of U-shaped cross-section, open at the top, and the plates 24 and 25 are seated on the open upper portion thereof. The die plate 24 (Fig. 8) is provided with a generally triangular opening 38 and the forward extremity 38^a thereof is adapted to snugly receive the lower end of the punch 26 while the larger rear end portion 38^b of said opening 38 receives the slit cutter or needle 27. Back of the opening 38 the shank of the plate 24 is provided with a somewhat elongated opening 39 through which the screw 30 passes. The main body portion of the die plate lies on the upper edge of the jaw 21 but at the rear of the plate the same is provided with a depending lug 40 extending down into the channel of the jaw so as to prevent lateral displacement of the plate relatively to the jaw. The screw 30 passes loosely through an opening in the bottom portion of the jaw 21, and it extends with some clearance through the elongated opening 39 of the die plate and into a threaded opening 41 of the stripper plate 25. The threads of the screw 30 engage the threads of the opening 41 and the stripper plate may therefore be tightly clamped with its shank 42 on top of the shank 43 of the die plate, which shank 43 is in turn tightly clamped to the supporting jaw. When the screw 30 is loosened, the elongated opening 39 of the die plate permits the longitudinal adjustment of the latter relatively to the jaw 21 and to the punch 26 so as to bring the die portion 38^a of the die plate into exact alinement with the punch 26. After this adjustment has been effected, the same may be maintained by again tightening the screw 30, as will be obvious. The lateral displacement of the stripper plate relatively to the jaw is prevented by means of a lug 44 similar to the lug 40 and extending alongside said lug 40 into the channel portion of the jaw 21. By this construction, the screw 30 is the only member sepa-

rate from the jaw and the plates 24 and 25, which is necessary to clamp said plates in position on the jaw, and yet this construction permits the ready adjustment of the die plate with reference to the punch. No lengthwise adjustment of the stripper plate is necessary owing to the fact that the opening 45 thereof through which the punch 26 passes should clear the punch to quite an appreciable extent, being somewhat larger than the die opening 38^a, while the opening 46 in the stripper plate for the slit cutter 27 also clears said slit cutter to a considerable extent lengthwise of the tool, as shown in Figs. 4 and 6. The projection 29 for operating the tongue inserter 28 is struck up from the stripper plate at the edge of the punch opening 45. The shank 42 of the stripper plate is slightly offset from the body portion thereof, as shown in Fig. 6, so as to provide a space 47 between the bodies of the die plate and stripper plate respectively, for the insertion of the sheets to be united.

The punch 26 is formed integral with the jaw 20. As previously stated, the jaw 20 is of channeled cross-section, and this permits the punch to be formed by bending down one end of the jaw on a rather gradual curve, after which the downwardly bent end is suitably worked and shaped to give it the desired cross-section. As shown in Fig. 3, the body portion of the punch 26 is narrower than the curved portion of the jaw 20 with which it is made integral. However, it will be noted that the front closed end of the punch merges into and forms a continuation of the upper closed portion of the jaw. Considerable difficulty has been encountered in forming the punch integrally with the jaw in this manner, but I have found that a construction substantially similar to that shown in the drawings is commercially practicable, and of course, the integral connection of punch and jaw eliminates a number of parts and takes off weight as compared to the old two piece construction.

The slit cutter or needle 27 is provided with a V-shaped cutting edge 27^a and an eye 27^b (Fig. 5). This slit cutter is made in the form of a flat plate having a shank 27^c snugly fitted between the walls of the jaw 20. A small pin or projection 27^d formed integral with the shank extends through an opening in the wall of the jaw and is clenched against such wall, after which the upset or clenched head of the pin or projection is finished off flush with the outer jaw surface. In the form shown, the body of the slit cutter is of a width corresponding to the width of the upper jaw and the edges of the body are set in notches 48 at the bottom edges of the jaw, as shown in Fig. 1. The pivoted tongue inserter 28 coöperating with the slit cutter 27 is pivot-

ed on a pin 49 connecting the side walls of the jaw 20 adjacent to the junction of said jaw with the punch 26. This member 28 has a depending arm 50 at one side of the 5 pivot adapted to coöperate with the eye 27^b of the needle or slit cutter, and at the other side of the pivot 49 the member 28 is provided with an arm 51 adapted to coöperate with the projection 29 of the stripper plate. 10 The member 28 is normally so suspended from its pivot that the arm 51 will lie in the path of the projection 29, whereas the arm 50 will be held out of the path of the projection 29 either by gravity (when the 15 jaws are horizontal, or are tipped downwardly relatively to the handles) or by contact of the tip of the arm 50 with the front face of said projection (when the jaws are tipped up relatively to the handles). By 20 preference the tongue inserter 28 will work on its pivot with a certain amount of friction so that its position will not be affected by the tilting of the implement, but in any case the jaws will be so spaced from each 25 other that the lower extremity of the arm 50 cannot pass over the upper end of the projection 29.

The operation of the improved tool in connecting together two or more sheets of 30 paper or like material will be apparent from the diagrams of Figs. 9 to 13 inclusive. The sheets having been inserted in the space 47 between the die plate and the stripper plate, the handles are manipulated to approach 35 the jaws toward each other. The punch 26 will pass freely through the opening 45 of the stripper plate into coöperation with the angular edges of the die opening 38^a, whereby registering tongues will be punched out 40 from the respective sheets in a downward direction, as shown in Fig. 9. At the same time the slit cutter 27 will cut a transverse slit through the sheets at a point comparatively close to the tongues, the eye of the 45 slit cutter being moved down beneath the lowermost sheet. This position of the parts is shown in Fig. 9. As the jaws continue to approach each other, the tip of the projection 29 will strike the arm 51 of the tongue inserter whereby the arm 50 of said tongue inserter will be moved toward the right with 50 reference to Figs. 6 and 9. In this movement, the lowermost extremity of the arm 50 engages the tongues, as shown in Fig. 10, 55 and as the jaws are further approached toward each other and as the projection 29 continues to rock the member 28 on its pivot, the extremity of the arm 50 will push the tongues through the eye of the slit cutter, 60 as shown in Fig. 11. It is then merely necessary to release the handles, which permits the jaws to move away from each other, thereby permitting the member 28 to swing

back by gravity to its initial position and causing the tongues to be carried upward 65 through the registering slits by the slit cutter, as shown in Fig. 12. The slit cutter then disengages the free extremities of the tongues, as shown in Fig. 13, and the operation is complete. In this manner the tongues 70 are carried sufficiently far into the slits to fasten the sheets together very firmly and securely. The stripper plate 25 acts in an obvious manner to clear the sheets from the punch and slit cutter as said punch and cutter ascend from the lower jaw. 75

While the foregoing description is necessarily a detailed one in so far as it concerns the particular embodiment of my invention selected for illustration and description, I 80 wish to have it understood that various modifications of the construction may be adopted within the scope of the appended claims.

What I claim is:

1. In a tool such as described, the combination of a channeled jaw having an open upper part, a die plate resting on the upper edge of said jaw and having a shank with an opening therein, a stripper plate having 90 a shank offset from the body portion thereof and resting on the shank of said die plate whereby the bodies of said die plate and stripper plate respectively are spaced apart, and a screw passing through the lower wall 95 of the jaw and through the aforesaid opening in said die plate into threaded engagement with the shank of said stripper plate, said opening of the die plate shank being larger than the diameter of said screw to 100 permit lengthwise adjustment of said die plate; substantially as described.

2. The combination with a jaw of substantially U-shaped cross-section, of a cutter comprising a plate having a shank fitted 105 between the side walls of the jaw, and a pin or projection on said shank extending through and clenched in an opening in the intermediate wall of the jaw; substantially as described.

3. The combination with a jaw of substantially U-shaped cross-section, the opposite edges of said jaw being provided with notches, of a plate having a body portion set in said notches, a shank on said plate 115 fitted between the side walls of the jaw, and a pin connecting the shank with the intermediate jaw wall; substantially as described.

In witness whereof, I have hereunto set 120 my hand on the 8th day of April, 1913.

WILLIAM A. BERNARD.
